Primary Examiner — Cynthia Ramirez

(74) *Attorney, Agent, or Firm* — Hovey Williams LLP

(57) **CLAIM**

The ornamental design for a collapsible floating receptacle, as shown and described.

DESCRIPTION

FIG. 1 is an upper perspective view of a collapsible floating receptacle shown in its extended configuration;

FIG. 2 is a side elevation view of the receptacle shown in FIG. 1 in its extended configuration;

FIG. 3 is an alternate side elevation view of the receptacle shown in FIG. 1 in its extended configuration;

FIG. 4 is still another side elevation view of the receptacle shown in FIG. 1 in its extended configuration;

FIG. 5 is a top view of the receptacle shown in FIG. 1 in its extended configuration;

FIG. 6 is a bottom view of the receptacle shown in FIG. 1 in its extended configuration;

FIG. 7 is an upper perspective view of the collapsible floating receptacle shown in its collapsed configuration;

FIG. 8 is a side elevation view of the receptacle shown in FIG. 7 in its collapsed configuration;

FIG. 9 is an alternate side elevation view of the receptacle shown in FIG. 7 in its collapsed configuration;

FIG. 10 is still another side elevation view of the receptacle shown in FIG. 7 in its collapsed configuration;

FIG. 11 is a top view of the receptacle shown in FIG. 7 in its collapsed configuration; and,

FIG. 12 is a bottom view of the receptacle shown in FIG. 7 in its collapsed configuration.

The broken lines in the figures are included for the purpose of illustrating portions of the collapsible floating receptacle and forms no part of the claimed design.

1 Claim, 10 Drawing Sheets
